UNITED STATES PATENT OFFICE.

PETER J. BRAUN, OF MILWAUKEE, WISCONSIN.

DESIGN FOR A GLOVE-BLANK.

SPECIFICATION forming part of Design No. 31,658, dated October 10, 1899.

Application filed July 31, 1899. Serial No. 725,694. Term of patent 7 years.

To all whom it may concern:

Be it known that I, PETER J. BRAUN, a citizen of the United States, residing at Milwaukee, in the county of Milwaukee and State of Wisconsin, have invented and produced a new and original Design for a Glove-Blank; and I do hereby declare the following to be a full, clear, and exact description of the same, reference being had to the accompanying drawing, forming a part thereof.

The said drawing is a plan view of a glove-blank embodying my new design.

My design relates to the new and original shape or configuration of the article.

15 The leading or essential feature consists in the unitary design for a glove-blank made the subject of illustration, comprising the shape of the hand portion A, thumb portion B, wrist portion C, and finger portions D, E, F, and G, the latter being of greater width than that of the other finger portions and having a nearly-vertical outer edge a, flaring outwardly slightly in its lower part b, the line of the lower end of the finger portion G extending upwardly and inwardly obliquely, as shown at c, and merging, by a rounded concave line d, with the downward and outward extending upper line e of the thumb portion

30 B. The outer end of the said thumb portion is formed on a rounded convex line f, continued on the lower side of the said thumb portion 35 on an upward and inward extending line g, merging, by a rounded concave line h, in a nearly-vertical downward-extending line i, which at the bottom is practically in line with 35 the vertical center of the finger portion F, the said line i forming one boundary of the wrist portion C, which latter is formed with a horizontal base-line j and a nearly-vertical upward-extending line k, which forms also the 40 boundary of the hand portion A and of the finger portion D on that side. The finger portions D, E, F, and G are all formed on practically parallel nearly-straight side lines and rounded convex top lines.

Having thus described my invention, what I claim as new, and desire to secure by Letters Patent, is—

45 The design for a glove-blank, as herein shown and described.

50 In testimony whereof I affix my signature in presence of two witnesses.

PETER J. BRAUN.
